UNITED STATES PATENT OFFICE.

GEORGE F. BRANDHUBER, OF PIERRE, SOUTH DAKOTA.

ENGINE-STARTER.

No. 836,559.

Specification of Letters Patent.

Patented Nov. 20, 1906.

Application filed June 29, 1905. Serial No. 267,519.

To all whom it may concern:

Be it known that I, GEORGE F. BRANDHUBER, a citizen of the United States, and a resident of Pierre, in the county of Hughes and State of South Dakota, have invented a new and Improved Engine-Starte, of which the following is a full, clear, and exact description.

The invention relates to a device intended particularly for starting internal-combustion engines; and my object is to provide an easier and safer means for starting the engine than the ordinary starting-crank and to enable the starting-gear to be placed in reach of a person seated in an automobile, so as to avoid the necessity of the automobile-driver alighting from the machine each time that the engine is to be started. I attain this end by providing a peculiar screw connected with the crank-shaft of the engine through the medium of a clutch. With this screw a peculiar non-rotary nut coacts, and the nut is actuated by a lever which in case the invention is applied to an automobile-engine extends up through the platform of the machine. By swinging the lever the nut may be advanced along the screw and the screw caused to rotate.

The invention resides in certain peculiar features of construction and combination of parts, all of which will be fully set forth hereinafter and pointed out in the claims.

Reference is to be had to the accompanying drawings, which illustrate as an example the preferred embodiment of my invention, in which drawings like characters of reference indicate like parts in the several views, and in which—

Figure 1 is a side elevation of the invention. Fig. 2 is a section taken through the nut. Fig. 3 is a side view of the same. Fig. 4 is a side elevation of a portion of an automobile and illustrating my improved starter as applied to the engine; and Fig. 5 is a vertical section on the line 5 5 of Fig. 4, illustrating one form of clutch mechanism which may be employed.

10 indicates one of the bearings of the crank-shaft 11 of the engine.

12 indicates the fly-wheel, and 14 a clutch member fastened thereto.

15 indicates a clutch member coacting with the clutch member 14. The clutch member 15 is fastened to a screw 16 and the clutch so arranged that rotation of the screw in the direction that the engine turns when

running ahead will cause this movement to be imparted to the crank-shaft 11, and when the engine takes up its normal operation the clutch will permit the crank-shaft to turn freely without imparting any movement to the screw. Any such form of clutch may be employed—as, for instance, that shown in Fig. 5. The screw 16 is preferably formed with a plurality of threads, and these threads decrease in pitch from the outer end of the screw to the inner end or that end which is adjacent to the fly-wheel. The purpose of this arrangement is to enable the nut upon the beginning of its movement to exert a relatively great leverage on the screw, and as this movement of the nut continues to turn the screw with greater speed. This permits the starting operation to begin slowly and with corresponding power and to end with a rapid movement. The outer end of the screw is mounted in a suitable bearing or support 17, and at its outer end directly adjacent to the bearing the screw is formed with an annular groove 18, which permits the screw to turn independently of the nut when the nut is engaged with the screw at this point. The result of this arrangement is that should the engine "kick back" or accidentally reverse its movement during the starting operation the nut will be thrown back to the outer end of the screw, and at reaching the groove 18 further movement of the nut or even strain thereon will cease, and the screw will be permitted to turn independently of the nut in either direction.

The nut comprises a collar 19, having pins 20 projecting from opposite sides and engaged in slots 21, formed in a bifurcated lever 22. This lever incloses the collar, as shown in Fig. 1, and is suitably fulcrumed, so that by swinging the lever the nut may be moved along the screw. According to the present embodiment of the invention the screw has three threads thereon, and the nut is provided with three balls 23, coacting, respectively, with these threads. The balls are permitted free movement in the collar, so as to reduce as much as possible the friction between the moving parts. The collar 19 is formed with three radially-extending internally-threaded openings 25, the inner ends of which are adapted to carry the balls 23, and the parts being so arranged that the balls will lie equidistant around the circumference of the screw, as Fig. 2 illustrates. The passages 25 contain screws 26, the inner ends of which are cupped to re-

ceive the balls, and 27 indicates lock-nuts which work on the screws 26 and are let into counter cavities 28, formed in the collar 19: By means of the screws 26 adjusting movement may be imparted to the balls 23, thus regulating the fit between the nut and screw and enabling wear to be taken up whenever necessary. The passages 25 also facilitate the assemblage of the parts.

- 10 In the operation of the invention the lever 22 should be manipulated so as to advance the nut from the outer to the inner end of the screw. Since the nut is non-rotary, this movement of the nut imparts to the screw a 15 rotation gradually increasing in speed. This rotary movement of the screw is transmitted to the shaft 11 through the clutch above described, and in this manner the engine is started. After the engine is started the nut 20 may be left engaged with the screw, or, if desired, the lever may be thrown to move the nut so that the balls 23 thereof engage the groove 18 in the screw. Should the engine kick back, the nut will be moved outward on 25 the screw, and upon reaching the groove 18 this movement will cease, as claimed above.

Having thus described the preferred form of my invention, what I claim as new, and desire to secure by Letters Patent, is—

- 30 1. The combination of an engine, a screw, a connection between the screw and engine-shaft, a non-rotary nut operating on the screw, and means for moving the nut, for the purpose specified, said screw having a gradu- 35 ally-decreasing pitch.
2. The combination of an engine, a screw, a connection between the screw and engine-shaft, a non-rotary nut operating on the screw, and means for moving the nut, for the 40 purpose specified, said screw having a pitch gradually-decreasing toward the end of the screw in connection with the engine.

3. The combination with an engine, of a screw, a clutch connecting the screw with the engine, a non-rotary nut operating on the 45 screw, and means for moving the nut along the screw, for the purpose specified, said screw having a decreasing pitch.

4. The combination with an engine, of a screw, a clutch connecting the screw with the 50 engine, a non-rotary nut operating on the screw, and means for moving the nut along the screw, for the purpose specified, said screw having a pitch gradually decreasing toward the end in connection with the engine. 55

5. In combination with an engine having a crank-shaft, a screw in alinement therewith, coacting clutch members on said shaft and said screw, a non-rotary nut on said screw, and means connected to said nut for moving 60 it toward and from the engine, the pitch of said screw being gradually decreased toward the end in connection with the engine whereby the speed of rotation of the engine crank-shaft is gradually increased as the nut is 65 moved along the screw at a constant speed.

6. In combination, a screw having a gradu- 70 ally-decreasing pitch, a non-rotary nut en- gaging said screw, a clutch member secured to the end of said screw, a pivoted lever con- nected to said nut, an engine having a crank- shaft, and means for connecting said clutch to said crank-shaft whereby the speed of rota- 75 tion of the crank-shaft is gradually increased as the lever is moved along the screw at a con- stant rate of speed.

In testimony whereof I have signed my name to this specification in the presence of two subscribing witnesses.

GEORGE F. BRANDHUBER.
